US0D1097668S

(12) **United States Design Patent** (10) **Patent No.:** **US D1,097,668 S**
(45) **Date of Patent:** **** Oct. 14, 2025**

(54) **AUTOMATIC LIQUID DISPENSING MACHINE**

(71) Applicant: **Lineng (Foshan City) Plastic Products Co., Ltd**, Foshan (CN)

(72) Inventor: **Ming Xie**, Foshan (CN)

(**) Term: **15 Years**

(21) Appl. No.: **29/875,812**

(22) Filed: **May 10, 2023**

(51) **LOC (15) Cl. 07-01**

(52) **U.S. Cl.**

USPC **D7/300**; D19/66; D8/30

CLAIM

The ornamental design for an automatic liquid dispensing machine, as shown and described.

DESCRIPTION

FIG. 1 is a top, front, right side perspective view of an automatic liquid dispensing machine, showing my new design;

FIG. 2 is a bottom, rear, left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the automatic liquid dispensing machine that form no part of the claimed design.

1 Claim, 8 Drawing Sheets
